[57] CLAIM

The ornamental design for an electrical test probe, as shown and described.

DESCRIPTION

FIG. 1 is a side elevational view of an electrical test probe showing my new design;

FIG. 2 is a top plan view thereof;

FIG. 3 is an end elevational view thereof on an enlarged scale as seen from plane 3—3 of FIG. 1;

FIG. 4 is an end elevational view thereof on an enlarged scale as seen from plane 4—4 of FIG. 1.

FIG. 1

FIG. 2

FIG. 3

FIG. 4
